UNITED STATES PATENT OFFICE

MENAHEM RIVKIN, OF PHILADELPHIA, PENNSYLVANIA

THROTTLE VALVE CONSTRUCTION

Application filed September 25, 1929. Serial No. 395,098.

One object of my invention is to locate the throttle valve of a locomotive in a cylinder structure.

A further object of the invention is to reduce the number of joints in the steam line to a minimum, and to eliminate a separate casting for the casing of the valve.

A still further object is to so locate the valve in the cylinder structure at the front 10 of the smoke-box that access can be readily had to it when adjustment or repairs are necessary. The invention also relates to the particular construction of the valve.

In the accompanying drawings:

15 Fig. 1 is an end view partly in section illustrating my improved throttle valve located in a cylinder casting of a locomotive, in which the steam pipes lead from the dry pipe or superheater;

20 Fig. 2 is a sectional plan view on the line 2-2, Fig. 1;

Fig. 3 is a sectional elevation on the line 3-3, Fig. 1;

25 Fig. 4 is an enlarged sectional view of the throttle valve shown in Fig. 1;

Fig. 5 is a plan view of the valve;

Fig. 6 is a detached plan view of the inner section of the valve;

30 Fig. 7 is a detached plan view of the ring; and

Figs. 8 and 9 are views illustrating modifications of the valve.

Referring to the drawings, 1 is a cylinder casting of any suitable type in the present instance, having cylinders 2-2 and steam chests 3 cast integral with the saddle 4. In the saddle are the steam supply passages 5 leading from the steam pipes 6 which are connected at their upper ends to a superheater header 6a or to the dry pipe of the locomotive. The boiler 7 is shown by dotted lines.

40 While two steam pipes 6 are shown, in some instances a single steam pipe may be used without departing from my invention.

The cylinder structure 1 is an integral casting, and in the casting is a partition 8 separating the live steam intake chamber 9 from the passages 10 leading to the steam chests 3-3. In the partition 8 is an opening 11 in which is fitted a seat ring 12 in the present instance for the main section 13 of the throttle valve 14.

On the stem 16 is a pilot valve 17 which is adapted to a seat 18 on the inner valve section 15 of the throttle valve. The valve section 15 is adapted to a seat 19 on the main section 13. On the stem is a nut 20 which can be adjusted so as to raise the second section after the pilot valve 17 is opened.

The lower end 21 of the inner section 15 is located in a chamber 22 formed in the hub 23 of a ring section 24, so that when the pilot valve is raised off its seat, steam admitted to the interior of the inner section 15 will act to balance the inner section of the valve so that it can be raised off its seat without effort; and as the movement of the stem continues the ring 24 will engage the shoulder 25 on the outer section of the valve, lifting said section 70 off its seat. When the valve is closed, any steam remaining in the inner section 15 will escape through the space between the hub 23 and the stem and through the radial passages 26.

75 The stem 16 is guided at its lower end in a bushing 27 located in a cavity in the cylinder casting, and the upper end of the stem is guided in a bushing 28 in a cover plate 29 which closes the top of the valve chamber 9. On detaching this cap plate the entire valve can be removed when necessary.

80 The valve 14 in the present instance is operated by a rod 40 extending to the cab of the locomotive and connected to an arm 30 on a shaft 31 which extends through a stuffing box 32 in the cylinder casting. On the end of the shaft 31, is an arm 33 bifurcated in the present instance and adapted to span the 85 90

valve stem, being secured to the stem by a pivot pin 34.

The arm 33 is so located that when it is detached from the valve stem it drops into a cavity 35 back of the line of the valve so that it will not obstruct the removal of the valve.

The bottom of the cavity for the lower bushing 27 is drained by a drain pipe 36, which in the present instance leads into the steam passage 10.

In Figs. 1 and 2 the throttle is located at the forward end of the saddle in front of the exhaust nozzles 37. This arrangement allows for easy access to the throttle valve without disturbing other parts of the mechanism within the smoke-box of the locomotive, but in some instances where necessary the valve may be located back of the exhaust nozzles without departing from the essential features of the invention. A drain pipe 38, provided for the valve chamber 9 as shown in Fig. 3, and a valve control the flow of water of condensation from this chamber. The valve may be operated with the cylinder cocks or independently, as desired.

In Fig. 8 is shown a modification of the valve shown in Fig. 4. The inner section 15a of the valve is raised by the stem 16a through the ring 24a. The ring also lifts the outer section 13a of the valve. The steam entering the inner section 15a when the pilot valve is raised escapes through lateral passages 39.

Fig. 9 illustrates a slight modification of the valve shown in Fig. 8. The inner section and the ring are independently mounted on the stem.

I claim:

1. The combination in a cylinder structure having cylinders therein, steam chests, and passages leading to the steam chests, of a live steam passage leading to a valve chamber; a partition separating the valve chamber from the passages leading to the valve chests; an opening in the partition; a valve seat located in the opening; a throttle valve mounted on the seat; a stem for actuating the throttle valve; a stuffing-box formed integral with the cylinder casting; and means for moving the stem.

2. The combination in a cylinder structure having cylinders therein; steam chests and passages leading to the steam chests; a live steam passage located above the passages leading to the steam chests; a horizontal partition separating the live steam passage from the passages leading to the steam chests; a central opening in the partition; a valve seat in said opening; a throttle valve mounted on the seat; and means extending to the outer side of said structure for actuating the valve.

3. The combination in a cylinder structure having cylinders therein; a steam chest for each cylinder; passages leading from a central point to the steam chests; a live steam

passage above the passage leading to the steam chests; a horizontal partition separating the two passages; an opening in the partition; a throttle valve located in the opening; a stem for the valve having upper and lower bearings in the structure; a horizontal shaft; an arm on the shaft connected to the valve; a second arm on the shaft on the outside of the structure; and a rod connected to the arm and extending to the cab of the locomotive.
